SPARK ARRESTER

John A. Johnson, Crawfordsville, Ind., assignor to
National Supply & Service Corporation, Craw-
fordsville, Ind.

Application June 4, 1934, Serial No. 728,925

14 Claims. (Cl. 183—98)

This invention relates to the art of spark arresters adapted to be placed over the tops of flues or chimneys.

In forming a spark arrester, it is necessary that any device applied to the flue must not interfere with the normal draft. A difficulty heretofore encountered, particularly as applied to residence or low draft flues, has been that the devices would become clogged with soot or lined with paper scraps and at times with snow and sleet, so that eventually, the flue draft would be so seriously reduced as to require the removal of the device. The problem, therefore, in eliminating the fire hazard arising from soot burning in the flue and from trash burning, is to provide some structure that will retain burning masses until either consumed, extinguished, or broken up into small particles and that will not cause a reduction of the draft in the flue by the filling in or the covering over of the structure by such masses.

It is a primary object of my invention to provide means for arresting the discharge of burning particles issuing from a flue until the particles are consumed or broken up into small masses less than that normally required to ignite wood. An important object of the invention is not only to arrest such burning particles as above indicated, but to break up the larger particles and allow the smaller particles to escape without clogging up the device to a point affecting the flue draft.

A further important object of my invention is to provide means automatically closing certain openings in the spark screen toward which particles of ignited matter may be blown by wind so that such matter will be retained during the presence of high winds until they have been consumed or broken up into inconsequential particles. In supplying this automatic means, it is the object of the invention to have such means operative only in the presence of high winds and even then to close only those openings on the lee side so as to leave openings uncovered on the windward side.

A further important object of the invention is to provide a series of openings in the wall of the screen graduated from small sizes toward the base to larger sizes in the upper part of the wall.

A still further important object of my invention is to provide a total effective outlet opening approximately that of the flue cross-section regardless of the amount of soot and the like leaving the flue. Other objects and advantages such as the extreme simplicity and relative low cost of production, will become apparent in the following

description of my invention as illustrated in the accompanying drawings, in which:

Fig. 1 is a side elevation of a structure embodying my invention;

Fig. 2, a top view in perspective of the automatically shiftable baffle;

Fig. 3, a top plan view of the structure, and

Fig. 4, a vertical transverse section on the line 4—4 in Fig. 3.

Like characters of reference indicate like parts throughout the several views in the drawings.

I form a foraminous receptacle with the base entirely open, the receptacle here being shown in the one particular form as rectangular in shape and made from woven wire in the nature of hardware cloth as it is popularly known. It is to be particularly noted that for a distance upwardly from the lower edge of the receptacle, the transverse or horizontally disposed wires are spaced closer together than they are thereabove. Preferably this close spacing extends approximately up from the base for one-third of the total height of the receptacle.

The receptacle is provided with a plurality of openings through the wall, here shown as one horizontally disposed opening in each of the four walls, the openings being designated by the numerals 10, 11, 12 and 13. Each of these openings is here shown as being at the same elevation and is formed by horizontally cutting through the vertically disposed wires to form a slit therethrough and further by cutting vertical slits in effect by cutting horizontal wires at the ends of the horizontal slit whereby the wall may be bent inwardly above the slit and also below the slit to form inwardly projecting flanges 14 and 15 integral with the wall. It is to be noted that the slit is made in each instance about midway between the adjacent horizontal wires or vertical wires in either case so that projecting ends of the wires are left to form spikes along the inwardly turned flanges. By means of this formation of the openings, it is to be observed that the openings are in effect spaced inwardly from the planes of the respective walls and that the under flange 15 slopes upwardly toward that opening while the upper flange 14 slopes downwardly toward that opening. These openings are preferably placed midway between the base and top of the walls, particularly where but one opening is employed in the wall as shown in Fig. 1.

The upper ends of the receptacle walls are curved around inwardly and thence downwardly to give an in and downturned flange 16 entirely around the upper ends of those walls. The inner

downturned edges of this flange 15 then define a rectangular opening into the receptacle from the top.

I form a closure 17 which in cross section is in 5 the form of a V. This closure is brought up against the under sides of the marginal edges of the flange 16 and there attached to underlap those edges so that the raw edges of the trough closure 17 are presented or directed upwardly. 10 This closure 17 is made of a foraminous material, preferably as herein shown, a woven wire of square mesh. The mesh of this material employed in the closure 17 is selected to have larger openings therethrough than are had in 15 the upper portion of the side wall of the receptacle proper. It is to be noted, however, that since the closure 17 is trough-like in nature and has its apex hanging downwardly from the top of the receptacle, the effective openings through 20 the closure 17 in a vertical direction do not exceed the actual openings through the side walls.

Referring again to the longitudinal openings through the side walls as represented by the numerals 10, 11, 12 and 13, the total combined area 25 of these openings is preferably made to be approximately equal that of the flue or stack to which the screen is to be applied. This combined area is therefore sufficient to take care of the normal draft through the stack should the screen 30 reach its maximum possible clogged position wherein all of the perforations become clogged through one cause or another.

As an added factor of safety, particularly in 35 such localities where high winds may prevail at certain seasons when the flue or stack is most liable to give off burning embers or particles of matter, I add a swinging baffle 18, Fig. 2 which is in effect an inverted wire basket although the material is not necessarily limited to wire since 40 any foraminous material would serve the purpose. Preferably the edges of the baffle 18 slope outwardly from the major base portion so that the edges are presented angularly in reference to the base. The baffle is employed in an inverted position to have those edges sloping downwardly and outwardly and on the base of the baffle in 45 this inverted position, I place and secure vanes 19 and 20, one at right angles to the other so that the one vane 19 extends upwardly from the longitudinal center line of the baffle while the other vane 20 extends upwardly from the transverse center line, the two vanes intersecting one another. The baffle 18 with these vanes attached 50 is swung within the receptacle by means of wire links 21 and 22 which are swingably connected to the closure 17 at its apex. The dimensions of the baffle 18 are selected to be such that when the baffle 18 is hanging in its normal central position as indicated in Fig. 1, there is an appreciable opening or clearance between the marginal edges of the baffle and the wall of the receptacle. This opening may be varied depending upon the degree of wind which is desired to 55 swing the baffle to its "closing" position. When the receptacle is mounted on the top of the flue or stack to which it is to be employed, the baffle 18 when the wind pressure becomes sufficient against the vanes 19 and 20 will swing the baffle against the lee side of the receptacle and the 60 lengths of the links 21 and 22 are so proportioned that in this swinging action under the wind pressure, the marginal edges of the baffle will come up under the respective flange or flanges 15 so as to cause the baffle to prevent 65 passage of any particles between the baffle and the 70

side wall of the receptacle on the lee side thereof. Thus the upcoming particles would strike against the underneath side of the baffle 18 and could not escape directly out through the horizontally disposed opening, 10, 11, 12 or 13 as 5 the case may be. However an increased opening is then provided on the windward side of the baffle 18, between the marginal edge of the baffle and the wall of the receptacle so that there would be no interference of the normal draft in 10 any event and regardless of the condition of the side wall of the receptacle. Of course as soon as the wind pressure decreased, the baffle would automatically return to its normally, centrally disposed position. 15

In some cases it would be entirely desirable to dispense with the closure 17 where the baffle 18 is employed, in which case the links 21 and 22 would be secured to the inturned marginal edges 20 of the flange 16.

In the normal operation of the spark screen, the ignited particles which are to be controlled would tend to rise vertically within the receptacle. Thus particles moving upwardly along the inside of the receptacle wall would be deflected 25 inwardly upon striking the under flange 16 at each of the horizontal openings, the actual contact therewith tending to break up those particles into smaller ones. Thus particles which would rise on past and strike the marginal flange 30 16 would have the choice of two directions. In one case the particles would be directed around to fall down along the inner side of the receptacle to drop onto the top flange 16 over each of the 35 horizontal openings so that the particles would be deflected inwardly. In the other case the particles would tend to fall around in the direction of the inturned end of the flange 16 and would strike the raw edge of the closure 17 in some instances and in others pass on down thereunder. Of course any projection, particularly 40 in a roughened state, especially when presented as spikes tends to break the particles in smaller units of less dangerous consideration. Those particles rising through the center of the receptacle, where the baffle 18 is not employed, and these particles would normally constitute the major quantity, strike the trough-like closure 45 17 which tends to spread the particles outwardly toward the side wall of the receptacle. The 50 angularity of the closure 17 on either side thereof is such that as the particles strike thereagainst and move therealong, a more or less grinding and comminuting action is produced so as to reduce the particles in size as well as to delay their 55 movement so as to permit a longer period of burning within the receptacle. Of course some of these particles may pass on through the perforations of the closure 17 but when they do so they are of such reduced size as to be non-hazardous in respect to igniting shingles on a 60 roof adjacent the stack.

Now when these particles roll on up the sides of the closure 17 and strike the flange 16, they are of course deflected around and down again 65 within the receptacle and by reason of the flange 16, tend to be directed back into the central upwardly moving current of the gases coming from the stack.

This operation has been described wherein little or no wind prevails across the top of the stack. Now when there is a wind, which exists most of the time, the particles will tend to be carried toward one side of the receptacle but the operation above indicated will be followed. If there 70 75

be a high wind, immediately the particles escape from the top of the chimney, they are carried against the opposite wall of the receptacle with some force and tend to adhere to that opposite wall. The area against which these particles strike is then generally limited to the lowermost portion of the wall and it is for this reason that the openings are reduced in size as compared to the openings in the upper portion of the wall. 5
10 The introduction of the baffle 18 within the receptacle as a further factor of safety gives the operation in addition as above indicated.

The variation in sizes of openings in the receptacle walls is an important feature in the structure. When the wind is strongest, the burning matter is swept almost entirely horizontally across the top of the chimney against the side wall of the receptacle. Therefore, the openings in the side wall within that height covering the path of such wind swept matter are reduced to that size wherein the matter passing on through is harmless, and at the same time, the openings thereabove are larger so as to preserve the desirable passages under low or no wind conditions, it being kept in mind, that under the high wind conditions, the sparks are hotter and smaller immediately they leave the chimney, than when they ascend vertically in the absence of wind. The larger openings will arrest the coarser and larger particles which reach them, whereas the smaller openings will arrest the hotter and smaller high velocity particles. The faster laterally moving particles require smaller openings to stop them than do the slower vertically moving particles. Moreover, those particles which otherwise would escape laterally from the receptacle under high speed conditions reach the danger zone of the roof quicker and in a much hotter condition than do the vertically ascending particles which would travel into the air vertically some distance and then descend, giving a time element for cooling of the particles before the roof is reached.

While I have herein shown and described my invention in the best form as now known to me, it is obvious that structural changes may be made therefrom, such, for example as in the materials employed to form the parts of the receptacle, proportions, and relative sizes of openings, without departing from the spirit of the invention, and I, therefore, do not desire to be limited to that precise form beyond the limitations as may be imposed by the following claims.

I claim:

1. For a chimney, a spark arrester comprising a foraminous walled extension above the chimney, and a baffle swingably carried within the wall subjected to being rocked by winds to reduce the opening between the baffle and the wall on the lee side and having an area less than the horizontal cross-sectional area of the extension.
2. For a chimney, a spark arrester comprising a foraminous walled extension above the chimney, and a baffle swingably carried within the wall subjected to being rocked by winds and having an area less than the horizontal cross-sectional area of the extension, and a foraminous top across the extension, the perforations in the top at least in part being larger than those in the side wall.
3. For arresting matter escaping from a chimney, a single foraminous wall forming in effect an extension of the chimney, said wall having horizontally disposed openings therethrough in addition to the perforations thereof, and having perforations of less size immediately above the chimney

ney than in the upper portion of the wall whereby particles of matter driven laterally by wind will tend to be retained in smaller sizes than those normally ascending to the upper wall portion, a top across said wall formed to extend arcuately around therefrom and down therewithin to have a V shape thereacross with its apex directed downwardly. 5
10

4. For arresting matter escaping from a chimney, a foraminous wall forming in effect an extension of the chimney, said wall having horizontally disposed openings therethrough in addition to the perforations thereof, and having perforations of less size immediately above the chimney than in the upper portion of the wall whereby particles of matter driven laterally by wind will tend to be retained in smaller sizes than those normally ascending to the upper wall portion, a top across said wall formed to extend arcuately around therefrom and down therewithin to have a V shape thereacross with its apex directed downwardly, said top being foraminous, and at least said V shaped portion of the top having larger openings therethrough than are in said wall. 15
20

5. For a chimney, a spark arrester comprising means for retaining sparks of a size normally arising from the chimney, and means for retaining smaller sparks swept laterally from the chimney under wind pressure, and means at the top of said smaller spark retaining means automatically shiftable by the wind for arresting rising of the sparks in the arrester above a predetermined level and preserving the normal draft of the chimney. 25
30

6. For arresting matter escaping from a chimney, a single foraminous wall forming in effect an extension of the chimney and having perforations of less size immediately above the chimney than in the upper portion of the wall whereby particles of matter driven laterally by wind will tend to be retained in smaller sizes than those normally ascending to the upper wall portion, a baffle swingably mounted within the wall, and vanes on the baffle subject to wind pressure to shift the baffle to the lee side of the wall to have the baffle substantially cut off a direct path from the chimney to the upper part of the wall. 35
40
45

7. For arresting matter escaping from a chimney, a foraminous wall forming in effect an extension of the chimney, said wall having horizontally disposed openings therethrough in addition to the perforations thereof, and having perforations of less size immediately above the chimney than in the upper portion of the wall whereby particles of matter driven laterally by wind will tend to be retained in smaller sizes than those normally ascending to the upper wall portion, a baffle swingably mounted within the wall to hang below the level of said horizontally disposed openings, and vanes on the baffle subject to wind pressure to shift the baffle to the lee side of the wall to have the baffle substantially cut off a direct path from the chimney through the lee opening, said baffle having less area than that of the passage formed from the chimney by the wall whereby normally a passageway is afforded around the baffle into the upper space within the wall above the baffle. 50
55
60
65

8. For arresting matter escaping from a chimney, a foraminous wall forming in effect an extension of the chimney, said wall having horizontally disposed openings therethrough in addition to the perforations thereof, and having perforations of less size immediately above the chimney than in the upper portion of the wall whereby particles of matter driven laterally by wind will tend to be retained in smaller sizes than those normally 70
75

ascending to the upper wall portion, a top across said wall formed to extend arcuately around therefrom and down therewith to have a V shape thereacross with its apex directed downwardly, a baffle of less area than the passageway defined by said wall, means rockably suspending the baffle from said top, and vanes on the baffle to cause the baffle to swing by wind toward the lee side of the wall.

10. For arresting matter escaping from a chimney, a foraminous wall forming in effect an extension of the chimney, said wall having horizontally disposed openings therethrough in addition to the perforations thereof, and having perforations of less size immediately above the chimney than in the upper portion of the wall whereby particles of matter driven laterally by wind will tend to be retained in smaller sizes than those normally ascending to the upper wall portion, a top across said wall formed to extend arcuately around therefrom and down therewith to have a V shape thereacross with its apex directed downwardly, a baffle of less area than the passageway defined by said wall, means rockably suspending the baffle from said top, and vanes on the baffle to cause the baffle to swing by wind toward the lee side of the wall, said baffle being suspended below said horizontal openings.

10. For arresting matter escaping from a chimney, a foraminous wall forming in effect an extension of the chimney, said wall having horizontally disposed openings therethrough in addition to the perforations thereof, and having perforations of less size immediately above the chimney than in the upper portion of the wall whereby particles of matter driven laterally by wind will tend to be retained in smaller sizes than those normally ascending to the upper wall portion, a top across said wall formed to extend arcuately around therefrom and down therewith to have a V shape thereacross with its apex directed downwardly, a baffle of less area than the passageway defined by said wall, means rockably suspending the baffle from said top, and vanes on the baffle to cause the baffle to swing by wind toward the lee side of the wall, said baffle being suspended below said horizontal openings, an inwardly extending flange across the under side of said horizontal openings substantially at the upper level of said smaller sized perforations.

11. For arresting matter escaping from a chimney, a foraminous wall forming in effect a ver-

tical extension of the chimney, said wall having perforations of less size toward the chimney end than that of the perforations toward the upper end, and having openings therethrough in addition to said perforations, inwardly directing flanges above and below said openings, and a foraminous top extending downwardly within the wall, said top having at least a sloping portion thereof provided with perforations larger in size than those in the wall.

12. For arresting matter escaping from a chimney, a foraminous wall forming in effect a vertical extension of the chimney, said wall having perforations of less size toward the chimney end than that of the perforations toward the upper end, and having openings therethrough in addition to said perforations, inwardly directing flanges above and below said openings, and a foraminous top extending downwardly within the wall, said top having at least a sloping portion thereof provided with perforations larger in size than those in the wall, said top being in effect a V-shaped trough dropped within the upper end of said wall, and said wall being curved around inwardly and downwardly to meet the trough.

13. For arresting matter escaping from a chimney, a foraminous wall forming in effect a vertical extension of the chimney, said wall having perforations of less size toward the chimney end than that of the perforations toward the upper end, and having openings therethrough in addition to said perforations, inwardly directing flanges above and below said openings, and a foraminous top extending downwardly within the wall, said top having at least a sloping portion thereof provided with perforations larger in size than those in the wall, said top being in effect a V-shaped trough dropped within the upper end of said wall, and said wall being curved around inwardly and downwardly to meet the trough, and a baffle swung from the trough within the wall to be normally below said openings, and means carried by the baffle to cause it to swing under wind pressure.

14. A spark arrester for chimneys and the like comprising a pair of elements, one within and spaced from the other and each having slotted openings, the slots of one element extending at right angles relative to the slots of the other element, said inner element being hung on said outer element for swinging movement relative thereto.

JOHN A. JOHNSON.
